John T. Voleau

UNITED STATES PATENT OFFICE.

HORACE E. BARKER, OF BROOKLYN, NEW YORK.

DENTAL DEVICE.

Application filed December 10, 1926. Serial No. 153,786.

This invention relates to means for cleaning and polishing the teeth and also for massaging the gums; having reference to a device which can be readily attached to or removed from a suitable stem or holder, as, for example, the mandrel of a dentist's hand piece.

The object of my invention is to provide a simple, inexpensive and efficient device for the purpose mentioned, which device is intended to be discarded after once using, thus lessening the danger of infection.

The invention comprises a tubular body of soft yielding substance, such as rubber, whereof one end is formed with elongated serrations, which present resilient spine-like rubbing members, said body being adapted to be detachably applied to a holder, and thereby manipulated in a manner to cause the serrations to effect the cleaning of the teeth and also the massaging of the gums without liability of injury to the tissues.

The invention also comprises such a serrated tubular member having a body of rubbering material snugly encased therein and adjustable relatively to the serrations, whereby the serrations not only protect the gums during the action of such material on the teeth, but also serve as a means to regulate the flexibility of the material.

The invention also comprises novel features of construction which will be herein-after described and claimed.

In the drawings—

Figure 1 is a side elevation of the device as applied to a mandrel, or similar holder.

Fig. 2 is a longitudinal section of the same.

Fig. 3 is a perspective view of the serrated tubular body.

Fig. 4 is a similar view of the tuft of bristles, detached.

Referring to the drawings, 10 designates a tube of yielding substance, such as soft rubber, having elongated spine-like resilient serrations 11 formed at and around one end. This tube is adapted to be detachably applied to the extremity of a suitable stem or holder, as, for example, the mandrel 12 of a hand piece, so that the serrated portion of the tube is somewhat distant from the holder. The mandrel 12 is provided with a protuberance 13 about which the tube is sprung and thereby detachably held in place, the body of the tube extending well along the mandrel to in-

sure the protection of the mouth of the patient from contact with the metal.

Within the tube 10 is snugly held by the constriction of the tube, a compact body of rubbing material, preferably a tuft of bristles 14, which abuts against the opposing extremity of the mandrel, and which body may be nicely adjusted in relation to the basal ends of the serrations by the act of moving the tube lengthwise of the mandrel. The tube is sufficiently constrictive to hold the bristles rigid in their positions of adjustment.

To use the device for cleaning or polishing the teeth the serrated end of the tube is held with sufficient manual pressure against the teeth to effect the outward spreading of the serrations until the brush contacts with the labial surfaces of the teeth. The serrations, by their inherent elasticity, conform to the contour of the teeth and insinuate themselves into the crevices and interdental spaces, thereby contributing to the efficiency of the cleansing operation, and also serving to protect the gingivæ from the frictional action of the bristles. By properly manipulating the device to effect the delicate pressure of the yielding spine-like serrations against the gums the latter can be efficiently massaged without liability of injury to the tissues.

The confined bristles 14 can be so adjusted in relation to the serrations that the former may be placed directly in contact with the tissues if desired, and thus act thereon in conjunction with or independently of the serrations. Moreover, by varying the adjustment of the bristles within the length of the serrations different degrees of stiffness or flexibility of the bristles can be attained to meet particular requirements.

If desired dental floss may be contained within the projecting end of the tube and saturated with a suitable cleansing or medicinal agent; or such agent, in paste or tablet form, may be contained in the tube. In either case the inner wall of the tube is preferably coated with paraffin or other suitable substance in order to protect the rubber against any chemical action that may develop from the presence of the cleansing or medicinal ingredients.

From the foregoing it will be seen that a device embodying my invention may be readily applied to or removed from one end of a stem, quill, or other manually operative

holder, and that when it is so applied the device may be efficiently manipulated with rotary, longitudinal or horizontal motions as the condition of the teeth or gums under 5 treatment may require.

I claim—

1. A dental device comprising a tube of soft resilient substance having resilient elongated spine-like serrations at and around one end 10 thereof, which form massaging fingers, the opposite end of said tube being adapted to be applied to a suitable holder.
2. A dental device comprising a tube of soft resilient substance having elongated 15 spine-like serrations at and around one end thereof, the opposite end of said tube being adapted to be applied to a suitable holder, and a body of rubbing material confined within said tube and adjustable longitudinally 20 thereof in relation to the serrations, whereby the degree of stiffness of the rubbing material can be varied.
3. A dental device comprising a rubber tube having elongated spine-like serrations 25 at one end thereof, the opposite end of said tube being adapted to be applied to a suitable holder, and a tuft of bristles snugly confined within said tube and adjustable longitudinally 30 thereof in relation to the serrations, whereby the degree of stiffness of the bristles may be varied.
4. A dental device comprising a tube having a yielding rubbing end portion, and a

tuft of bristles snugly confined within said tube and adjustable longitudinally of said 35 tube in relation to the rubbing end portion, whereby the degree of stiffness of the bristles may be varied, said tube being adapted to be applied to a suitable holder which is also arranged to form an abutment for the 40 tuft of bristles.

5. The combination with a mandrel having a retaining protuberance, of a rubber tube tightly encasing said protuberance and extending along the adjacent portion of the 45 mandrel, said tube projecting outward and having at and around its free extremity elongated spine-like tapered serrations which form massaging fingers.

6. The combination with a mandrel having 50 a retaining protuberance, of a rubber tube tightly encasing the protuberance and extending along the adjacent portion of the mandrel, said tube projecting outward and having at and around its free extremity elongated spine-like tapered serrations, and a 55 tuft of bristles snugly confined within said tube and adjustable longitudinally thereof together with the mandrel in relation to the serrations whereby the degree of stiffness of 60 the bristles may be varied.

Signed at New York, in the county and State of New York this 30th day of November, A. D. 1926.

HORACE E. BARKER.
